UNITED STATES PATENT OFFICE.

EDWARD PIERCE, OF WEST BURLINGTON, IOWA.

CUT-OFF SAW.

Application filed April 1, 1918. Serial No. 225,939.

To all whom it may concern:

Be it known that I, EDWARD PIERCE, a citizen of the United States, residing at West Burlington, in the county of Des Moines and State of Iowa, have invented certain new and useful Improvements in Cut-Off Saws, of which the following is a specification.

This invention relates to a cut off saw adapted for use in cutting pipe and the like, and the invention may be employed either for cutting off the rough end of a pipe or for cutting the pipe for forming an acetylene weld.

The principal object of the invention is to provide an improved saw operated by compressed air or the like and adapted to be operated conveniently and efficiently for cutting pipe. An important feature of the invention is the provision of novel means for holding pipe in position for receiving either a square cut, or an inclined cut adapted for the purpose of acetylene welding. A further object is to provide improved means for driving the saw and for actuating the same when in use. A further feature relates to novel means for holding the pipe to be operated upon by the saw. Other objects relate to various features of construction and arrangement which will appear more clearly hereinafter.

The nature of the invention will be understood from the following specification taken in connection with the accompanying drawings in which one embodiment of the machine is illustrated.

In the drawings—

Figure 1 shows a side elevation of my improved apparatus;

Fig. 2 shows an end elevation, looking toward the right as viewed in Fig. 1, with parts thereof broken away;

Fig. 3 shows a top plan view of the machine illustrating a pipe held in position to have the end thereof cut off transversely to its longitudinal axis;

Fig. 4 shows a partial top plan view of the machine illustrating a pipe held in position for receiving an inclined cut adapted for the purpose of forming an acetylene weld;

Fig. 5 is a detail sectional view taken on the line 5—5 of Fig. 3 looking in the direction of the arrows, showing the adjustable plate for regulating the height of the pipe being operated upon by the machine;

Fig. 6 shows two pipes placed together

for acetylene welding after being operated upon by the machine in the manner illustrated in Fig. 4; and

Fig. 7 shows a partial side elevation of the motor casing with a part thereof broken away to show the driving connection to the shaft of the saw.

The machine illustrated in the accompanying drawings comprises a supporting frame 10 having two end frames 11 each having a leg 11^a inclined in a plane extending longitudinally of the machine and a leg 11^b inclined in a transverse plane, these legs being constructed, preferably of angle iron form. The end frames are connected at the forward side of the machine by a transverse frame member 12, and the frames 11 are also connected adjacent the lower part of the machine by transverse frame members 13 of angle iron form which extend between opposite pairs of legs 11^a and 11^b. The legs 11^a and 11^b of each end frame 11 are connected by frame members 14. These members form a rigid supporting structure which may be conveniently moved and readily secured in any desired position.

The frame 10 supports an air motor housed within a cylindrical casing 15 which is mounted in the enclosure formed by the frame and supported thereon by means of the inlet pipe 16 and the exhaust pipe 17, which extend from and are secured to opposite sides of the cylinder of the motor in alignment with each other to form stub shafts adapted to be journalled in bearing members 18 carried by the frame members 13, previously described, to which they are secured by bolts 19. The motor is preferably of the radial vane type, being operated by compressed air or the like, which is introduced through the pipe 16 and exhausted through the pipe 17. The flow of compressed fluid through the pipe 16 is controlled by a main operating valve 20 having a valve stem 20^a pivotally connected to an operating lever 21 having a handle 21^a adjacent the upper part of the machine. The lower end of the lever 21 is pivoted at the point 22 on a bracket 23, which has bifurcated arms 23^a clamped to the casing of the valve 20. The valve 20 communicates with an elbow 24 from which a pipe extends downwardly and communicates with the horizontal extension 16^a of the inlet pipe which leads from a suitable source of compressed air supply. The extension 16^a of the inlet pipe extends horizontally

105
110

beneath the motor and is suspended from the exhaust pipe 17 by a hanger 25. An oil cup 26 is mounted above the valve 20 and communicates therewith for the purpose of oiling the valves, motor and cylinders. The operating lever 21 moves through a slot 27 in the lever guard 28, which is carried by the adjacent frame member 13 and one of the legs 11^a. When the lever 21 is operated to open the valve 20, compressed fluid is admitted to the motor, and the shaft thereof is rotated to drive the mechanism hereinafter to be described.

The extension 30 of the casing of the motor 15 forms a housing for the motor shaft 31 and also encloses the gears through which the motor shaft is connected to the spindle 32 of the saw. The housing 30 is closed at its upper end by a cap 33 in which the end of the shaft 31 is journaled, and this shaft is preferably connected to the spindle 32 through a worm 34 which is fixed thereon and arranged to mesh with a worm gear 35 carried by the spindle 32 extending transversely to the shaft 31 and mounted in a lateral extension 30^a of the casing 30. The worm and worm gear are lubricated by means of a grease cup 36. The saw 37 is fixed on the projecting end of the spindle adjacent the forward side of the machine, and the other end of the shaft is engaged by the saw spindle nut 38. A standard 39 extends upwardly from the cap 33 of the housing 30 and carries an oil pot 40 having a valve 41 adjacent the lower part thereof located over the saw 37 and controlled by an operating handle 41^a. This valve may be regulated to cause the desired flow of oil onto the saw when the latter is in operation. The oil which drains off of the saw is collected by a waste oil trough 43 mounted beneath the saw and extending longitudinally of the frame to which it is connected by suitable brackets 44 or the like. A drain pipe 45 leads from the trough 43 to a waste oil can 46, in which the oil is collected.

The saw 37 and the driving mechanism therefor are oscillated to engage the work to be operated upon by means of a feed screw 48, which extends along the inside of the waste oil trough 43 and is journaled in suitable bearings 49 carried by the frame of the machine at the opposite ends of the trough. This feed screw is operated by a hand wheel 50 having a handle 50^a, and it engages a feed nut 51 having a lug projecting therefrom to engage the slot 52 of the feed nut slide 53 carried by the extension 30 of the motor casing. When the feed screw 48 is rotated in a clockwise direction, the movement of the feed nut 51 will oscillate the casing of the motor about its bearings 18 carried by the frame, and thus cause the saw 37 to be moved toward and through the work to be operated upon. It will be

observed that during this operation the entire driving mechanism oscillates and that the oil feed for the saw is carried bodily with the saw, so that the feed of oil thereon remains constant during its operation.

When using the saw for forming a square end on a pipe, the pipe 55 is held between jaws 56 and 58 which have V-shaped faces provided with corrugated surfaces adapted to exert a firm grip upon the surface of the pipe. These jaws are mounted on an auxiliary jaw frame 60, which is secured to the transverse frame member 12 at the upper part of the machine. The jaw 58 is fixed on the post 60^a at one end of the frame 60, and the pipe 55 is forced against this jaw by means of the movable jaw 56 which is detachably mounted on the piston rod 63. The piston rod is slidably mounted in the post 60^b, and the connection of the jaw 56 to the piston rod is preferably made by means of a vertically-extending T-shaped tongue 61^a on the piston rod and a similarly shaped groove or slot 61^b in the rear face of the jaw. The jaw normally slides on the frame 60, but when desired the jaw may be removed from the piston rod and suspended at the side of the machine by means of a chain 62, which is connected to the post 60^b of the frame 60 located opposite the post 60^a. The air cylinder 64 is carried by the post 60^b and extends laterally therefrom. A piston 65 is mounted on the piston rod 63 within the enlarged end portion 64^a of the cylinder, and when compressed air is admitted thereto, the piston and piston rod are moved in a forward direction to cause the jaw 56 to engage the pipe. When the compressed air is shut off, the piston and jaw are returned to their normal positions by means of a coiled spring 66 mounted on the piston rod within the reduced portion 64^b of the cylinder. The flow of compressed air to the cylinder 64 is controlled by an inlet valve 68 having a handle 68^a, and the air flows through this valve from a pipe 69, preferably of copper or the like, which extends downwardly and communicates with the inlet pipe 16 on the discharge side of the air valve 20, so that when the main valve 20 is open air will be admitted to the cylinder 64, provided the valve 68 is open. The jaws 56 and 58 are adapted to operate on different sizes of pipe, and to permit a firm support of the material being operated upon, regardless of its size, there is provided an adjustable supporting block 70 carried by the frame 60 and having a slot 70^a to receive the saw 37. The block 70 has a vertically extending tongue 71 adapted to slide in a vertical groove, or guide-way, 72 formed in the face of the post 60^a, and the position of the supporting block may be adjusted by means of a bolt 73 which extends through a vertical slot 74 130

in the post and is engaged at its other end by a clamping nut 75.

When the machine is to be used for forming an inclined cut 76 upon the end of a pipe 55^a, as shown in Fig. 6, the pipe is held in the position shown in Fig. 4, between two other jaws 77 and 78 which are carried by another jaw frame 79 mounted on the frame 10 transversely to the jaw frame 60. One of these jaws 78 is mounted in fixed position on the post 79^a at one end of the frame 79, and the other jaw 77 is slidably mounted on the supporting frame and connected to a piston rod 80, which extends into the air cylinder 81 carried by the frame 79 and provided with a piston 82 and a spring 83, whereby the piston rod 80 is actuated when air is admitted to the cylinder and is returned to normal position by the spring when the air is cut off. Air is admitted to the cylinder 81 through another valve 84 to which air is introduced through a pipe 85 leading from the discharge side of the main valve 20. When the cylinder 81 is to be used, the valve 84 is opened and the valve 68 controlling the flow of air to the other cylinder 64 is closed. The opening of the main valve 20 will then admit air to the cylinder 81 and will cause the jaws 77 and 78 to grip and hold the pipe 55^a, as shown in Fig. 4. When using the machine for cutting a pipe held between the jaws 77 and 78, the pipe 55^a is provided with a bend 55^b inwardly from the jaws, and the projecting end 55^c of the pipe is directed over the frame 60, previously described, and against the jaw 58. The jaw 56 may preferably be removed during this operation and suspended at the side of the machine by means of the chain 62. Then when the saw is moved forwardly by the operation of the feed-screw 48, the pipe 55 will be held firmly by the jaws 77-78 and will be supported against the jaw 58, so that a clean cut can be made through the pipe in an inclined direction.

It will be apparent that when using the machine for forming a straight cut or a welding cut, the jaws are set in operation to grip the piece as soon as the air is turned on through the main valve 20, provided the controlling valve 68 or 84 has previously been opened, and, at the same time, the saw 37 begins to operate, so that after opening the main valve 20 it is only necessary to begin operation of the feed screw 48 by turning the wheel 50, thereby moving the saw 37 into engagement with the piece. The saw is thus very conveniently operated and a firm gripping of the piece is insured when the saw is in operation. It will be understood that when one of the air cylinders 64 or 81 is in operation, the air valve for the other cylinder should be closed. After completing the cut through the pipe or the like, the

lever 21 may be operated to close the main valve 20, whereby the saw will be stopped and the jaws automatically separated to release the body of the pipe. The feed screw is then operated in the reverse direction to return the saw to its normal position.

Although I have shown and described a single embodiment of the invention for purposes of illustration, it will be understood that it may be constructed in widely different forms without departing from the scope of the appended claims:

What I claim is:

1. In apparatus of the class described, a motor having a casing, a saw carried by said casing on a shaft disposed at an angle to the shaft of said motor, means for gearing said shafts together, means for holding a piece to be operated upon, and means for moving said casing and said saw to bring the latter into engagement with said piece.

2. In apparatus of the class described, a motor, a casing therefor, oppositely disposed stub shafts mounted on said casing, bearings for said shafts, a saw carried by the casing of said motor and driven thereby, means for holding a piece to be operated upon, and means for oscillating said motor on said shafts to move said saw into engagement with said piece.

3. In apparatus of the class described, a frame, a motor movably mounted in said frame with its shaft extending in an upwardly direction, a saw spindle carried by the casing of said motor, a saw mounted on said spindle, means for gearing said spindle to the shaft of said motor, means for holding a piece to be operated upon, means for moving said casing to bring said saw into engagement with said piece, and means movable with said saw for supplying oil thereto.

4. In apparatus of the class described, a frame, a motor movably mounted in said frame, a saw spindle carried by the casing of said motor, a saw mounted on said spindle, means for holding a piece to be operated upon, a feed nut operatively connected to the casing of said motor, and a feed screw mounted in said frame and engaging said nut for moving said casing and thereby bringing said saw into engagement with said piece.

5. In apparatus of the class described, a frame, a fluid operated motor having inlet and outlet pipes forming supporting shafts therefor, bearing members mounted on said frame and engaged by said pipes, means for controlling the flow of fluid through said pipes, a cutting tool movable with said motor and operated thereby, and means for moving said motor about said bearings for bringing said cutting tool into operative position.

6. In apparatus of the class described, a frame, a fluid operated motor having inlet

- and outlet pipes forming supporting shafts therefor, bearing members mounted on said frame and engaged by said pipes, means for controlling the flow of fluid through said pipes, the casing of said motor having an extension, a spindle mounted in said extension and operated by said motor, a cutting tool mounted on said spindle, and means engaging the extension of said casing for oscillating said motor about said bearings to bring said cutting tool into operative position.
7. In apparatus of the class described, a frame, a motor pivotally mounted in said frame, the casing of said motor having a hollow extension, a saw spindle mounted in said extension, means also mounted in said extension for connecting said saw spindle with said motor, a saw mounted on said spindle, and means for controlling the pivotal movement of said motor for moving said saw into engagement with the work operated upon.
8. In apparatus of the class described, a frame, a pair of jaws mounted on said frame, means for removing one of said jaws, a saw mounted adjacent said jaws, means for moving said saw into and out of engagement with a piece held by said jaws, and adjustable means for supporting the end of said piece opposite said saw.
9. In apparatus of the class described, a frame, a pair of relatively movable jaws mounted on said frame, a third jaw also mounted on said frame and disposed adjacent said first named jaws in such wise that the end of a curved piece of work clamped between said first named jaws may engage said third jaw, a saw, means for actuating said saw, and means for moving said saw into engagement with said piece.
10. In apparatus of the class described, a frame, a pair of relatively movable jaws mounted on said frame, a saw, means for simultaneously actuating said saw and one of said jaws, and means for moving said saw into engagement with a piece held by said jaws.
11. In apparatus of the class described, a frame, a motor movably mounted in said frame with its shaft extending in an upward direction, a saw spindle carried by the casing of said motor, a saw mounted on said spindle, means for gearing said spindle to the shaft of said motor, means for holding a piece to be operated upon, and means for moving said casing to bring said saw into engagement with said piece.
12. In apparatus of the class described, a frame, a motor pivotally mounted thereon with its shaft disposed upwardly, a casing for said motor and said shaft, a saw blade carried by said casing near the upper end of the same and being adapted to be driven from said shaft by means of said motor, means for holding the work to be operated upon, and means for moving said casing in such wise as to bring said saw into engagement with said work.
13. In apparatus of the class described, a frame, a motor pivotally mounted on said frame, a saw blade carried by the casing of said motor on a shaft disposed at an angle to the motor shaft, means for gearing said shafts together, and means for oscillating said motor about its pivots to bring said blade into engagement with the work to be operated upon.
14. In apparatus of the class described, a frame, a fluid-operated motor having inlet and outlet pipes forming supporting shafts therefor, means for controlling the flow of fluid through said pipes, a cutting tool movable with said motor and operated thereby, means for moving said motor about said shafts for bringing said cutting tool into operative position, fluid-actuated clamping means for the work to be operated upon, and a connection between said clamping means and said inlet pipe whereby upon actuation of said controlling means said cutting tool and clamping means are simultaneously operated.
15. In an apparatus of the class described, a frame, a motor pivotally mounted thereon on an axis angularly disposed relatively to the motor shaft, a saw blade carried by the casing of said motor and operated by the latter, and means for oscillating said motor on its pivots to operatively position said saw blade.
16. In an apparatus of the class described, a frame, a fluid motor movably mounted thereon, a saw blade carried by the casing of said motor and operated by the latter, means for moving said motor to operatively position said saw blade with respect to the work, means for clamping said work in position to be operated upon, and means for simultaneously actuating said saw and said clamping means.
17. In an apparatus of the class described, a frame, a fluid operated motor pivotally mounted thereon on an axis angularly disposed relatively to the motor shaft, the pivots of said motor constituting the inlet and outlet for the same, a saw blade carried by the casing of said motor and operated by the latter, means for oscillating said motor to operatively position said saw blade with respect to the work, clamping means for the latter, and a connection between said clamping means and said inlet whereby upon the opening of the latter said saw blade and clamping means will be simultaneously actuated.

In testimony whereof, I have subscribed my name.

EDWARD PIERCE
